UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed February 12, 1930. Serial No. 427,691.

My invention relates to a slicing machine and has for one purpose the provision of a slicing machine having a reciprocating or generally rectilinear edged knife. Another 5 object is the provision of such a machine in which such a knife is associated with a guard and gauge plate lying in generally parallel planes, in association with a readily movable, for example, a manually movable carriage. Other objects will appear from time to time in the course of the specification and 10 claims.

I illustrate my invention more or less diagrammatically in the accompanying drawings, wherein—

Figure 1 is a side elevation with parts in section;

Figure 2 is a perspective view of a knife;

Figure 3 is a section on the line 3—3 of 20 Figure 1;

Figure 4 is a section on the line 4—4 of Figure 1;

Figure 5 is a section on the line 5—5 of 25 Figure 1;

Figure 6 is a section on the line 6—6 of Figure 1;

Figure 7 is a horizontal section illustrating 30 one formation of the rear edge of the knife in relation to the adjacent guard plate;

Figure 8 is a similar section illustrating a 35 different formation of the rear edge of the knife; and

Figure 9 is a detail section of a variant form of knife bearing.

Like parts are indicated by like symbols 40 throughout the specification and drawings.

Referring to the drawings, A generally indicates any suitable base which may be supported for example upon the yelding supporting members A¹.

Mounted upon the base A is any suitable motor means, diagrammatically illustrated as the motor A², as shown in Figure 3. A³ generally indicates an upstanding housing or frame portion mounted upon

the base A, and including a rear wall A⁴, an end wall A⁵ and a more or less inclined or arcuate side wall A⁶. The pulley shaft A⁷ may extend through any suitable aperture in the wall A⁴ and may terminate for example in a drive pulley A⁸. A⁹ indicates any suitable

guard plate, which might be formed integrally with the housing A³, but is preferably movable therefrom, as herein shown. Any suitable means for adjusting the guard plate in relation to the knife, below described, may be 55 employed. I have illustrated one form of adjustment, which has been found satisfactory. The guard plate A⁹ may be formed with a plurality of depressions A¹⁰ adapted to receive the heads of the screws A¹¹ the screw 60 stems of which pass through apertures A¹² of larger diameter to allow for lateral minute adjustment. A¹⁴ are adjustable plugs screw-threaded into bosses formed integral with the housing A³. The plugs A¹⁴ are internally 65 threaded as at A¹⁵ to receive the screws A¹¹ by means of which the depressed portions A¹⁰ of the guard plate A⁹ are held securely against the heads of the plugs A¹⁴ as shown in Figure 3.

B generally indicates a cylindrical track mounted upon forward projections B¹ from the base A. Illustrated as vertically aligned with the track B is the guide track B² similarly mounted upon the base A. Slidable along 70 the two tracks is the work supporting carriage generally indicated as B³ which may include the work engaging portion proper B⁴ pivoted as at B⁵ and adapted either to be left in horizontal position, as shown in Figure 1 or to be tilted to various positions. As 75 tilting and supporting means I illustrate the pivoted links B⁶ slotted as at B⁷, and in operative engagement with the locking knob B⁸. B⁹ is an upstanding work engaging flange or 80 abutment along the edge of the member B⁴ which is remote from the cutting edge of the knife when the carriage is in the initial position in which it is shown in Figure 1.

I may employ a pusher plate C slidable for 85 example along the pin or guide C¹ and also, if desired, rotatable thereabout, a connecting sleeve C² being employed which is adaptable also for use as a manual handle for the combined operation of moving the carriage along 90 the tracks and of urging the pusher plate C toward the cutting plane. C³ is a connection between the pusher plate C and the sleeve C², which is also available for use as a manual handle, in case the operator wishes to thrust 95 100

the pusher plate directly toward the cutting plane, as when the other hand is used to move the carriage. In practice it is more common to employ the sleeve C^2 as a single handle for effecting both purposes. C^5 indicates a guard 5 associated with the carriage B^3 and preferably formed as a unit with or secured to the meat supporting member B^4 . At its right hand edge, as shown in Figure 1, it may be 10 secured to the upstanding portion C^6 which is 15 in effect an upward projection of the flange B^9 , upwardly extended adjacent the cutting plane of the knife.

D generally indicates a gauge plate which 20 may be mounted upon any suitable supporting means D^1 upstanding from the movable housing D^2 . The details of gauge plate actuating means do not of themselves form part 25 of the present invention. I illustrate, however, a manual knob D^3 , in response to rotation of which the gauge plate may be moved 30 forwardly into or rearwardly out of the cutting plane. Preferably its path of movement, whether arcuate or rectilinear, may effect simultaneously a rearward movement of 35 the gauge plate rearwardly away from the cutting plane, and a lateral movement of the gauge plate laterally away from the cutting edge of the knife. The result is to open the 40 throat between the opposed edges of knife and gauge plate, as the gauge plate is rearwardly moved. D^4 is any suitable guard member 45 preferably associated with the gauge plate, and overhanging the rear face of the knife and protecting its edge from the rear at all normal positions of the gauge plate.

E generally indicates the knife body which 50 includes the blade portion proper E^1 and the terminal guide blocks E^2 , herein shown as 55 generally rectangular in cross-section, but which may be formed to suit any desired shape of guide.

Referring to Figure 1 it will be seen that 60 the knife is in generally upright position. Preferably its edge defines a generally vertical cutting plane which plane is preferably 65 parallel with the faces of gauge and guard plates, and generally parallel with the path of movement of the carriage B^3 across said gauge and guard plates. I may provide any 70 suitable means for supporting the upper and lower ends of the knife but I illustrate a lower bearing block E^3 which may form part of or be associated with the base A and an upper bearing block E^4 which may be mounted 75 for example upon an upward and lateral extension E^5 of the housing wall A^6 . These bearing blocks contain the aligned apertures E^6 which correspond in dimensions and 80 shape to the members E^2 at the ends of the knife E .

I may provide any suitable means for reciprocating the knife within its bearing guides but I find that the structure herein 85 shown is satisfactory. Referring to Figure

6 the lower guide block E^3 is illustrated as secured, as by the screws E^7 to a portion of the base A . Upstanding from the rear face of the knife is a bearing pin E^8 which may be screwthreaded into the knife as at E^9 . 70 Rotatable thereabout is the sleeve portion E^{10} at the end of the link E^{11} eccentrically pivoted to the pulley E^{12} adapted to rotate in response to the belt E^{13} which in turn passes about the drive pulley A^8 . Any suitable means for supporting the pulley E^{12} may be employed but I illustrate the pulley shaft E^{14} mounted in the roller bearings E^{15} . E^{16} indicates a spacer or spacing sleeve interposed between the rear face of the knife and 80 the member E^{10} . E^{17} indicates any suitable and preferably removable cover plate for the top of the block E^4 which serves to close the top of the aperture E^6 .

It will be realized that rotation of the pulley E^{12} will impart to the knife E a rapid reciprocation. It may be desirable, as indicated in Figure 9, to employ yielding means tending to urge the knife upwardly after the downward thrust, in order to increase the 90 readiness of return of the knife and in order to prevent rattling. I therefore illustrate the spring G which may be coiled about the guide portion G^1 surrounding the end E^2 of the knife and compressed against the plate G^2 which may be secured as by the screw G^3 to the upper end of the knife. 95

Referring for example to Figure 3 I illustrate a close approach between the edge of the guard plate A^9 and the rear edge of the knife. I illustrate variant forms of the opposed edges of knife and guard plate for example in Figures 7 and 8. In Figure 7 the rear edge of the knife E is shown as convex and the opposed edge of the guard plate A^9 as concave, reversing the formation of the parts shown in Figure 3. In Figure 8 the rear edge of the knife is provided with a lateral extension E^{20} which penetrates an opposed aperture E^{21} . It will be understood 100 that in all forms there will be sufficient tolerances allowed to prevent any substantial wearing contact between knife and gauge plate, although it may be preferable to provide quite a close contact in order to limit 105 the penetration of material therebetween and to provide a flush surface over which the work may pass after the slice has been severed by the cutting edge.

It will be realized that whereas I have 110 described and shown a practical and operative device, nevertheless many changes might be made in the size, shape, number and disposition of parts. I therefore wish my 115 description and drawings to be taken as in a broad sense illustrative and diagrammatic rather than as limiting me to my specific showing.

The use and operation of my invention are 120 as follows:

I have illustrated the application of a reciprocating knife to a light type of manually operable machine. That is to say, all operations are manually performed except the 5 actual movement of the knife. The knife is given a rather short, rapid reciprocation, it being held of course in a single cutting plane. The work to be sliced is positioned upon the carriage, resting upon the work support B⁴ 10 and the carriage is moved past the cutting edge of the knife. The gauge plate D is set to determine the thickness of the slice. As the gauge plate D is at all times in general parallelism with the path of movement of 15 the carriage, the thickness of the slice is uniform from edge to edge and there is no cramping between the face of the work and the guard plate A⁹, as the work crosses the guard plate after the slice is removed. 20 Guard and gauge plates are at all times in generally parallel planes. I find it preferable to make the front edge of the knife E conform generally to the plane of the guard plate A⁹. Similarly, the knife being bevelled, as shown in Figures 3, 7 and 8, I prefer to form the wall A⁶ of the housing either in general continuation of the bevel of the knife, or inclined back sufficiently to prevent any interference with the severed slice as 25 it is delivered from the knife for receipt upon the slice receiving element or tray H. Referring to Figure 1 it will be seen that the knife, although lying in vertical plane, is inclined in that plane, so that the cutting edge overhangs the body of the work as it is moved toward the knife. Therefore the work is to some extent wedged between the overhanging knife edge and the work support B⁴ and the slice support E²⁵. The result of this 30 wedging action is to hold the work firmly against the cutting edge and to insure a clean, quick slice, with a minimum of dragging or larding or frictional resistance. The actual speed of movement of the knife edge in relation to the work is slight as compared, for example, to the electrically driven rotary knives of machines now on the market. Therefore, the result is a great reduction in 35 the tendency of the work to heat and a reduction in the formation of lard and grease in slicing such materials as ham or bacon. The present device has many advantages over the rotary knife machine now on the market. A reciprocating knife blade is much less expensive than the ordinary disc knife. No sharpening device is required on the machine, as the reciprocating knife is so arranged as to be readily removable from the machine. Referring for example to Figure 40 1 all that is necessary is to unscrew the pin E⁸, thus releasing the lower edge of the knife. The knife can then be either dropped downwardly through the bearing block E⁹ or drawn upwardly through the bearing block E⁴, the cover plate E⁷ being removed in 45 the latter case. The cutting angle on the reciprocating knife is constant for the entire height of the cutting space, whereas in the circular knife the cutting angle is constantly changing. The reciprocating knife is free 50 from any tendency to draw particles of grease or meat back into the inside of the machine. A directly reciprocating movement provides no opportunity for drawing meat particles or grease back into a closed 55 housing. In fact, as shown in Figure 3 both edges of the blade are exposed sufficiently for adequate cleaning, the only non-enclosed part being the very slight area of opposition to the guard plate A⁹, and the slight length 60 of the guide blocks E³ E⁴. The slower edge speed of the knife, however, practically eliminates the larding difficulty, so often met with in high speed rotary knife machines, and there will be little or no grease or lard to deal 65 with.

The employment of the reciprocating knife enables the use of a light, simple, small housing for the knife transmission and eliminates the necessity for the bulky bearing and bearing sleeve now employed in rotary knives. The provision of proper means for deflecting the slice and for receiving it upon the receiving tray H is rendered easy, since there is little or no tendency on the part of a reciprocating knife to grip the slices or to distort them or to throw them centrifugally in response to the rotation of the rotary knife. 70

It being possible to make the edge of the knife perfectly straight, fitting the edges of the gauge and guard plates to the adjacent edges of the knife is rendered easy. The task of guarding the edge of the knife is rendered easy since only that portion of the edge which is actually used for slicing is exposed. 75

I claim:

1. In a slicing machine a base, a generally plane guard plate mounted upon said base, a gauge plate mounted on said base and lying in a plane generally parallel to the plane of the guard plate, means for moving said gauge plate toward and away from the plane of said guard plate while maintaining it constantly in general parallelism with the guard plate, a work support and means for guiding it across the faces of the gauge and the guard plate along a path generally parallel with said faces and a reciprocating knife positioned between the opposed edges of gauge and guard plate, and guiding means on the upper and lower ends of said knife, said guiding means being positioned respectively above and below the normal cutting edge or zone opposed to the work. 80
2. The structure of claim 1 characterized by the employment of the knife having guiding or bearing blocks at each end thereof, the intermediate portion of the knife being unsupported. 85

3. The structure of claim 1 characterized by the employment of aligned bearing sleeves for the upper and lower ends of the knife, the knife having guiding or bearing blocks at each end thereof adapted to engage said sleeves.

4. In a reciprocating knife for use with slicing machines, a knife blade and guide or bearing blocks at each end thereof, said blocks being integral with the knife blade, said blocks being formed with longitudinally aligned bearing surfaces, the knife blade portion lying within the peripheries of said blocks.

15 5. The structure of claim 4 characterized in that the knife blade, which connects the blocks, is unsupported intermediate its ends and is of sufficient cross-sectional area to maintain itself in accurate longitudinal alignment with said blocks.

20 6. In a slicing machine, a work support and means for guiding it, a reciprocating knife positioned adjacent the path of movement of said work support for reciprocation in a generally vertical plane, a positive drive adapted to reciprocate said knife, said drive being adapted to cooperate with the lower end of the knife, and yielding means opposed to said drive, said yielding means being normally 25 under compression between an upper portion of the knife and the guiding means.

30 7. In a slicing machine, a guard plate, a gauge plate, means for maintaining the gauge plate in parallelism with the guard plate, the 35 opposed edges of said guard and gauge plates being rectilinear and parallel, a rectilinear knife positioned in the space between said opposed parallel edges and means for guiding it for movement along a rectilinear path, 40 means for reciprocating said knife, and a work support and means for guiding it across the faces of gauge and guard plate and knife along a path generally parallel with said faces, the cutting plane defined by the cutting 45 edge of the knife being generally parallel with the planes of gauge and guard plates, said knife being inclined from the vertical, the edge of said knife overhanging the work mounted on the carriage as the carriage is 50 thrust against the knife, the angle defined by the cutting edge of the knife and the path of movement of the carriage being at all points along the cutting edge of the knife substantially less than a right angle.

55 8. In a slicing machine, a work support and means for guiding it, a reciprocating knife and means for reciprocating it, a guard plate and a gauge plate positioned in planes normally parallel, the cutting plane of the 60 knife being in parallelism with the guard and gauge plate, motor means and a driving connection between the motor means and knife, and a closed transmission housing to the rear of the guard plate, said guard plate 65 being adapted to serve as a closure for said

housing and being removably mounted in relation thereto.

Signed at Indianapolis county of Marion and State of Indiana, this 18th day of January, 1930.

70 WILLIAM J. CAMPBELL.
